UNITED STATES PATENT OFFICE.

ELMER N. STACY, OF MINNEAPOLIS, MINNESOTA, ASSIGNOR TO DECARIE INCINERATOR COMPANY, OF MINNEAPOLIS, MINNESOTA, A CORPORATION.

INCINERATOR.

1,211,979.

Specification of Letters Patent.

Patented Jan. 9, 1917.

Application filed November 28, 1913. Serial No. 803,528.

To all whom it may concern:

Be it known that I, ELMER N. STACY, citizen of the United States, resident of Minneapolis, county of Hennepin, State of Minnesota, have invented certain new and useful Improvements in Incinerators, of which the following is a specification.

In the operation of discharging a load of garbage or other refuse into an incinerator, it has sometimes happened that a person has accidentally fallen through the opening into the incinerating chamber.

The object of my invention is to provide a form of hopper which will be closed at the bottom during the operation of dumping the load, and may be opened to discharge its contents into the incinerating chamber after the opening leading to the hopper has been closed.

My invention consists generally in various constructions and combinations, all as hereinafter described and particularly pointed out in the claims.

In the accompanying drawings forming part of this specification, Figure 1 is a longitudinal, vertical, sectional view of an incinerator embodying my invention, Fig. 2 is a vertical sectional view on the line $x-x$ of Fig. 1.

In the drawing, 2 represents the wall of the incinerator, and 3 the incinerating or combustion chamber, provided with a header 4 communicating at each end with circulating pipes 5 which extend to a circulating cylinder 6 provided on each side of the incinerator. Circulating pipes 7 lead from the header 4 through the wall of the incinerating chamber to the cylinder 6. These pipes or tubes coöperate with the header 4 to form the basket or grate into which the material to be consumed is discharged. Above the incinerating chamber is a platform 8 provided with openings 9 therein through which the garbage or other refuse material is discharged. These openings are provided with suitable covers 10. Beneath these openings I provide hoppers 11 and 11^a, each divided vertically into independent sections hinged at 12 on suitable supporting flanges 13. These hopper sections are adapted to swing apart at their lower ends to allow the material therein to slide down by gravity through openings 14 in the top of the combustion chamber of the incinerator. Normally the hop-

pers will be closed and entrance to the combustion chamber prevented. Any suitable means may be provided for separating the hopper sections, but I prefer to provide a shaft 15 having a worm wheel 16 meshing with a worm 17 on an operating rod 18. A belt 19 connects the shaft 15 with a shaft 20. The shaft 20 has a crank arm 21 connected by a link 22 with a section of the hopper 11. The shaft 15 has a crank 23 connected by a link 24 with the other section of the hopper 11^a. At the opposite end of the combustion chamber is a horizontal shaft 25 operated through the medium of a worm rod corresponding to the one described and which I will indicate by the same reference numeral, with the addition of the exponent "a". This shaft 25 has a belt connection 19^a with a shaft 20^a located between the hoppers and provided with a crank 21^a that is connected with one section of the hopper 11 by a link 22^a and a shaft 25 has a crank 26 connected by a link 24^a with the other section of the hopper 11. When the rods 18 and 18^a are operated, the shafts 15 and 25 will be rocked and the sections of the hopper separated to allow its contents to be discharged by gravity into the incinerating chamber beneath. The operating rod 18^a is diagonally mounted in the platform with respect to the opposite rod 18, one rod being on one side of the platform and the other rod on the opposite side, as indicated by the drawing. This will be done after the openings 9 are closed by the placing of the covers 10 thereon. From this construction it will follow that there will be no possibility of a person falling into the incinerator with the garbage or during the operation of dumping the refuse into the incinerator.

Any suitable means may be provided for connecting the hopper sections with the links of the operating mechanism, but I prefer to provide brackets 27 formed on the lower portions of the outer walls of the hopper sections. These brackets have under surfaces which are adapted to cover the openings 14 leading to the combustion chamber and are adapted to slide over the top of the combustion chamber to expose fully the openings from the hoppers into the chamber.

The arrangement of the hopper sections with converging lower walls and the mech-

anism for operating these sections assures the rapid discharge of the contents of the hopper, for no matter how sticky or wet the refuse material may be, the hopper sections may be worked back and forth against one another to dislodge any portion of the refuse which may be clinging to the hopper walls.

In various ways the details of construction herein shown and described may be modified and still be within the scope of my invention.

I claim as my invention:

1. The combination, with an incinerating chamber having a filling opening in the top thereof and a platform surmounting said incinerating chamber and spaced therefrom and also having a filling opening to register with the opening in said incinerator, a flange fitting within said platform opening and having a suitable cover, a hopper divided vertically into separable sections hinged on said flange and having means at its lower end for normally closing the opening in said incinerator, and mechanism for separating said sections to expose said incinerator opening and discharge the contents of said hopper therein.
2. The combination, with an incinerating chamber having a filling opening in the top thereof, of a hopper divided vertically into separable sections above said filling opening, the lower ends of said sections having brackets thereon provided with under surfaces for closing said filling opening when said sections are brought together, and means for separating said hopper sections to allow the contents thereof to discharge into said incinerating chamber.
3. The combination, with an incinerating chamber having a filling opening in the top thereof, of a hopper divided vertically into separable sections and having brackets at its lower end provided with under surfaces for closing said filling opening when said

sections are brought together, rock shafts having arms and link connections with said brackets, mechanism for operating said shafts to move said hopper sections toward and from one another, and a platform having a filling opening provided above said hopper sections.

4. The combination, with an incinerating chamber having a filling opening in the top thereof, of a hopper having substantially straight upper walls and converging lower side walls and divided vertically into separable sections, each section having a pivotal support for its outer wall at its upper end, means for closing said filling opening when the sections of said hopper are brought together, and means for separating said hopper sections to discharge the contents thereof into said incinerating chamber.

5. The combination, with an incinerating chamber having a filling opening in the top thereof and a platform surmounting said incinerating chamber and spaced therefrom and also having a filling opening, a hopper divided vertically into independent sections, said sections being hinged at their upper ends beneath and adjacent to said platform and upon opposite sides of the opening therein, the lower walls of said hopper sections converging and positioned to direct the contents of the hopper into the opening in the top of the incinerating chamber, the lower ends of said hopper sections having a limited movement for separating them to expose the opening into said incinerating chamber, and means for operating said hopper sections simultaneously.

In witness whereof I have hereunto set my hand this 19th day of November, 1913.

ELMER N. STACY.
